(57) **CLAIM**

The ornamental design for a lunch box for kids, as shown and described.

DESCRIPTION

FIG. 1 is a perspective view of a lunch box for kids showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view thereof when the lunch box for kids is closed.

The broken lines shown in the figures depict portions of the lunch box for kids that form no part of the claimed design.

1 Claim, 9 Drawing Sheets
